[57] **CLAIM**

The ornamental design for a vehicle starter cable, as described and shown.

DESCRIPTION

FIG. 1 is a front view of a vehicle starter cable illustrating my new design;

FIG. 2 is a left side view thereof;

FIG. 3 is a right side view thereof;

FIG. 4 is a rear view thereof;

FIG. 5 is a top view of the main control plug seen in the upper portion of FIG. 4;

FIG. 6 is a bottom view of the main control plug seen in the upper portion of FIG. 4;

FIG. 7 is a top view of the smaller plug seen in the lower portion of FIG. 4, the control plug being omitted for clarity; and,

FIG. 8 is a bottom view of the smaller plug seen in the lower portion of FIG. 4, the control plug being omitted for clarity.

The termination of the cable between the two plugs indicates a cable of indeterminate length.
